UNITED STATES PATENT OFFICE.

WALTER G. SEABOLD, OF ALTON, ILLINOIS, ASSIGNOR TO ILLINOIS GLASS COMPANY,
OF ALTON, ILLINOIS, A CORPORATION OF ILLINOIS.

PACKING-CASE FOR CARBOYS.

1,320,713.

Specification of Letters Patent.

Patented Nov. 4, 1919.

Application filed April 12, 1918. Serial No. 289,734.

To all whom it may concern:

Be it known that I, WALTER G. SEABOLD, a citizen of the United States of America, a resident of Alton, in the county of Madison, State of Illinois, have invented certain new and useful Improvements in Packing-Cases for Carboys, of which the following is a full, clear, and exact description, reference being had to the accompanying drawings, 10 forming a part of this specification.

My invention relates to a packing case for use in transporting large bottles, commonly known as carboys, and has for its object the construction of a packing for such cases 15 made of strong and durable cushioning devices of simple and inexpensive nature which may be expeditiously arranged in the packing case bodies, and which afford a very high degree of protection to prevent breakage of 20 the carboys and insure greater safety in handling.

Figure I is a perspective view of my packing case, the cover or lid being shown open and partly broken away.

25 Fig. II is a plan view of the case, the cover or lid being omitted.

Fig. III is a vertical section through the case in open condition, with one of the corner packing strips shown only partially inserted.

30 Fig. IV is a perspective view of the bottom cushion device of my case.

In the drawings, A designates the rectangular body of my packing case provided with a suitable cover or lid B.

35 Within the body of the case A is a bottom cushioning device C which rests upon the bottom of the case and serves to yieldably support a carboy centrally positioned within the case and surrounded by the cushioning members to be hereinafter described.

40 The bottom cushioning device C serves to so yieldingly support the carboy as to prevent damage thereto by shock imposed upon the packing case in a vertical direction, and 45 said device comprises the following elements, viz., a base board 1 resting on the bottom of the case body A, a block 2 of smaller dimensions than the base board resting centrally upon said base board, a lower

50 spring board 3 resting on said block and an upper spring board 4 resting upon and extending transversely of the lower spring board. The lower spring board is surrounded by carboy-receiving blocks 5 and the upper board is surmounted by carboy-

receiving blocks 6, the top surfaces of all of said blocks 5 and 6 being in the same horizontal plane so that a carboy placed within the packing case body A will rest uniformly on all of said blocks and be supported thereby. All of the parts of the carboy-supporting device C are preferably of wood and the spring boards 3 and 4 are of wood veneer. By making the spring boards of wood veneer it is possible to make them of such thinness 65 that they will readily yield under sudden pressure imposed by the carboy supported by said spring boards, and at the same time of such toughness that they will not be broken due to the force of any shock that 70 may be delivered against them by vertical movement of the carboy. This result is possible, as will be apparent, owing to the veneer board being made up of a plurality of plies of wood in which the grain of the 75 different plies cross each other.

The body of the carboy is protected by a cushioning means, which will be next described. Approximately midway between the side edges of each wall of the case body 80 A, within said case body, are thin cushion strips 7, preferably of wood veneer, which are spaced from the wall of the case body by distance blocks 8, located between said cushion strips and the body wall. The 85 blocks 8 at the upper ends of said strips are preferably secured to the case body A, while blocks at the lower ends of the strips may be free of connection to said body, as seen in Fig. III. The cushion strips 7 are so separated from the body A of the packing case by the distance blocks 8 that they will contact with the exterior of a carboy positioned between them and afford as many cushions for the wall of the carboy as there are cushion strips 7. It should be noted that the distance blocks 8, back of the cushion strips 7, are shorter than the width of said strips, and therefore the margins of the strips extend beyond the distance blocks, as clearly 95 seen in Figs. I and II.

9 designates thin corner cushion strips, preferably of wood veneer, extending diagonally of the case body A and interposed between the thin side cushion strips 7. 105 These corner cushion strips are of such width that they will extend from the distance blocks 8 back of one of the side cushion strips 7 to the distance blocks 8 back of the next adjoining side cushion strip 7, lo- 110

cated at a right angle to the first mentioned side strip, and also beyond the marginal edges of said side strips approximately into contact with the ends of the spacing blocks 5 8. Each of the corner cushion strips 9 is provided at its outer side with upper and lower distance blocks 10 located at the top and bottom ends of the strip, said distance blocks being of such length that they will 10 engage the adjoining walls of the packing case body, as seen in Fig. II, when the corner cushion strips are in position. Therefore the side edges of the corner cushion strips are confined back of the marginal edges of the side cushion strips and 15 wedged between the spacing blocks 8 back of said side strips and adjoining walls of the packing case body. Consequently, the corner cushion strips may be readily slipped 20 vertically into place diagonally of the corners of the case body A, and when completely positioned within the body back of the marginal portions of the side cushion strips, will be firmly held without any se- 25 curing means for attaching them to the packing case body. In Fig. III I have shown one of the corner cushion strips only partially inserted into the case. It will be apparent that when it is completely lowered 30 into the case it will be interlocked between the side cushion strips and the case body, due merely to frictional engagement as de- scribed.

The several cushion strips 7 and 9 are all 35 preferably of wood veneer, this material being used on account of yielding nature and toughness to afford the desired and necessary yielding action in cushioning the carboy which contacts with the several cushion strips and is protected at all points 40 throughout its circumference thereby. Consequently, a jar in any direction cannot injure the carboy and there is no liability of breakage of the cushion members. 45 It will be apparent that the herein de- scribed packing is inexpensive, and that it may be very expeditiously arranged in the case body A, the only procedure necessary in establishing the packing being the secur-

ing of the side cushion strips 7 to the walls 50 of the packing case body and the insertion of the corner cushion strips by merely slipping them into place between the side packing strips in a manner to cause interlocking engagement between said corner packing 55 strips and said side packing strips.

I claim:

1. The combination with a packing case body, of carboy cushioning means within said body comprising side cushion strips 60 spaced from walls of said body, and corner cushion strips removably held by said side cushion strips.

2. The combination with a packing case body, of carboy cushioning means within 65 said body comprising side cushion strips spaced from walls of said body, and corner cushion strips extending across the corners of the case body and removably interlocked between the case body walls and said side 70 cushion strips.

3. The combination with a packing case body, of carboy cushioning means within said body comprising side cushion strips spaced from walls of said body, and corner 75 cushion strips having their side edges located back of the side margins of said side cushion strips, said corner cushion strips being provided with distance members en- gaging walls of said case body and holding 80 the margins of the corner cushion strips in engagement with the margins of said side cushion strips.

4. The combination with a packing case body, of carboy cushioning means within 85 said body comprising side cushion strips spaced from walls of said body, said side cushion strips being wider than the means by which they are spaced from the walls, and corner cushion strips interposed be- 90 tween the means for spacing said side cushion strips from the walls and having their side margins located back of the side mar- gins of the side cushion strips.

In testimony that I claim the foregoing I 95 hereunto affix my signature.

WALTER G. SEABOLD.
